CLAIM

The ornamental design for a ceiling fan motor housing and light kit combination, as shown and described.

DESCRIPTION

FIG. 1 is a top perspective view of a ceiling fan motor housing and light kit combination shown in the environment of a ceiling fan, showing our new design;

FIG. 2 is a bottom perspective view thereof;

FIG. 3 is a top plan view of the motor housing and light kit combination, having the ceiling fan environment removed;

FIG. 4 is a bottom plan view thereof;

FIG. 5 is a front [side] elevation view thereof; and,

FIG. 6 is a right side elevation view thereof.

Portions of the ceiling fan environment and the ceiling fan motor housing and light kit combination are shown in broken lines. Portions shown in broken lines form no part of the claimed design.

1 Claim, 6 Drawing Sheets

Matter enclosed in heavy brackets [ ] appears in the original patent but forms no part of this reissue; matter printed in italics indicates the additions made by reissue.
